United States Patent Office

Des. 188,110
Patented June 7, 1960

188,110

DEMOUNTABLE ELECTRIC STORAGE BATTERY CASE

Robert Broussard, Glendale, and Charles A. Toce, Sun-
land, Calif., assignors to Electro-Acid Corporation, a
corporation of Nevada

Filed Sept. 25, 1958, Ser. No. 52,770

Term of patent 14 years

(Cl. D26—6)

FIG. 1

FIG. 2

Fig. 1 is a perspective view of a demountable electric storage battery case, showing our new design; and

Fig. 2 is an end perspective view thereof.

The opposite side and end, not shown, have substantially the same appearance as the side and end shown.

We claim:

The ornamental design for a demountable electric storage battery case, as shown and described.
